UNITED STATES PATENT OFFICE.

JAMES G. DICKSON, OF LITTLE ROCK, ARKANSAS, ASSIGNOR TO DIXN MANUFACTURING COMPANY, OF GREENWOOD, MISSISSIPPI, A CORPORATION OF WEST VIRGINIA.

SAW-GIN.

1,010,732.

Specification of Letters Patent.

Patented Dec. 5, 1911.

Application filed July 22, 1910. Serial No. 573,336.

To all whom it may concern:

Be it known that I, JAMES G. DICKSON, a citizen of the United States, residing at Little Rock, county of Pulaski, State of Arkansas, have invented certain new and useful Improvements in Saw-Gins; and I do hereby declare the following to be a full, clear, and exact description of the invention, such as will enable others skilled in the art 10 to which it appertains to make and use the same.

This invention relates to saw gins, and it aims to provide certain improvements in the construction shown in my application, 15 Serial Number 500,843, filed June 8, 1909. In that application I have described effective means for removing the trash, such as motes, leaves and the like, from the lint on the revolving saw teeth and carrying such 20 trash out of the machine by means of an air blast.

According to the present invention, the trash is not only removed from the machine by means of the air blast, but the latter is 25 also used to remove the cleaned lint from the saws, the air for both of these purposes being taken from the same source.

The novel features of the invention will appear clearly from the following description and claims.

In the accompanying drawing the single figure is a diagrammatic transverse section of a gin constructed in accordance with the invention.

35 In the drawing, A denotes a gang or battery of the usual circular saws, in connection with which the ordinary gin ribs B, one of which is partially shown, are employed. These ribs may be arranged in any appropriate way, without affecting the gist of the 40 invention, but they are preferably applied to an upper cross beam C, as shown.

The mechanism constructed in accordance with the present invention, and adapted to 45 remove the trash from the lint on the saw teeth as well as to carry off the cleaned lint from the saws, is arranged at the rear of the battery of saws A. It comprises a comparatively large air flue D into which air is 50 forced at one end, by means of an opening such as indicated at E, from a fan or similar source (not shown). This air flue leads completely across the gin, as will be understood, that is to say it is substantially co- 55 extensive in length with the gang or bat-

tery of saws A, to which it has a substantially parallel relation. Leading laterally from the lower part of the air flue D is an extension F by means of which the air in the flue is directed laterally, in the direction 60 of the saws, between upper and lower boards or plates G, H, as shown. In the embodiment illustrated, the board G which is uppermost, is substantially or approximately horizontal, while the lower board H has an 65 upward inclination with respect to the saws. At the rear of the latter, that is, behind the ribs B and above the lateral extension F, is a trash chamber I conforming generally to the peripheries of the saws and into 70 which the trash is thrown by centrifugal force after passing through the ribs on the lint carried by the saw teeth. The upper wall of the trash chamber I is formed by a curved plate i, while the lower part of this 75 chamber is constituted by laterally adjustable plates i', i''. Between the lower edge of the curved upper plate i and the lower edge of the plate i', a slot or aperture i''' is created, and this slot or aperture communicates directly with a lateral trash duct or 80 dust chute J which is substantially parallel with the air flue extension F, above the same, and debouches into a trash flue K extending across the gin in the space between the upper 85 portion of the air flue D and the trash chamber I. A portion of the air forced through the extension F of the air flue passes through a reversely directed air duct 90 or nozzle f which is so formed as to turn 95 back the air entering the mouth of said duct from the extension F, and direct it into the trash duct J, substantially at the junction of the latter with the trash chamber I. In the embodiment shown, the discharge duct f for delivering air into the trash flue comprises upper and lower branches disposed at opposite sides of a thin plate f' on the upper board G, said branches being in parallelism so that the direction of 100 the air will be wholly reversed as it is discharged into the trash duct, and the duct f is of reduced cross section at its point of discharge in order to obtain a strong draft in the trash duct. The duct f discharges 105 into the trash duct immediately below the plate i'', in the embodiment shown, and said plate is adjustable laterally, by means of a slotted connection embodying a plurality of screws i'', to control the width of the slot 110

or aperture i^3 . The plate or whipping board i^2 extends into proximity to the saw teeth, and it can also be adjusted, relatively to said teeth, by the screws i^4 just mentioned, which 5 pass through both of the plates in question. Another portion of the air in the air flue extension F is discharged into the intermediate portion of the trash duct J by means of a short duct j in the intermediate part 10 of the board G, and in this way the draft in the aforesaid trash duct is considerably augmented. After the trash passes longitudinally through the trash flue K, it is discharged at one end thereof (toward the 15 observer, as shown), being thus removed from the machine. Of course there is a strong draft through the flue K to effect this result, and a whirling movement is given to the longitudinally moving air by 20 the direction of the inlet of the trash duct into said flue in a substantially tangential direction, as shown. A small branch pipe d may also discharge tangentially into the flue K from the main flue D in order to increase 25 this whirling effect, and at the same time to prevent the lodging of trash in the flue K and facilitate the discharge of such trash from the opposite end of the flue.

As has been previously intimated, I not 30 only aim to remove the trash from the lint on the saw teeth and from the machine but also to remove the lint itself, after being cleaned, from the saw teeth. In order to effect this result, the extension or air duct 35 F is provided at its lower portion with a small duct f^* , discharging adjacent the battery of saws, as shown. This discharge duct, which is below the trash removing mechanism and at the extremity of the air flue ex- 40 tension F, is preferably formed between an edge of the board H and an adjustable plate f^* , similar to the plates previously described. This plate f^* , has a downturned edge which deflects the discharging air in a down- 45 ward direction against the saw teeth, so that it is eventually discharged in line with the axes of the teeth when the latter reach the lower part of their rotary movement, as will be understood. The ducts or nozzles f , f^* 50 are preferably formed by the provision of a dividing block G' interposed between the dust chute and the condenser chute and forming in connection therewith air blast passages respectively leading into the 55 mouths of the chutes, the nozzle to direct a blast of air into the dust chute being directed into the latter between the lower wall thereof and the whipping board.

In the operation of the machine, the saws 60 are rotated in the direction of the arrow, and the centrifugal force induced will throw the trash on the lint passing through the ribs B over against the upper or outer plate i of the trash chamber I. The plates l' and i^2 65 are adjusted to suit existing conditions, and

the trash falling out of the bottom aperture or slot i^3 of the trash chamber will pass directly into the lateral air blast in the dust chute J. The action of the air in the discharge duct f and in the trash flue K will 70 be readily understood from the foregoing description. Of course the lint which is cleaned passes on with the saw teeth and finally into the path of the blast issuing from the duct f^* , whereby all of the cleaned 75 lint is blown from the saws into a condenser chute M below the board H and from said condenser chute out of the machine, this operation being assisted by discharging air from the flue D through a port h into the 80 space below the board H, in the direction indicated by the arrows. The plate or whipping board i^2 may be used to exert a positive stripping action on the trash or may not, and it will be understood, of course, that 85 trash falling on the plates i , i^2 will slide downward, by gravity, to the discharge aperture i^3 communicating with the trash duct in which the blast of air is maintained.

Without limiting myself to the construction shown, I claim:—

1. In a saw gin, the combination with the saws, of means to direct a blast of air in proximity to but out of contact with the peripheries of the saws in order to remove the 95 trash thrown off from the saws, and means to direct a blast of air against the lint on the saw teeth from which the trash has been removed.

2. In a saw gin, the combination with the 100 saws, of means to direct a blast of air toward the saws, means to direct a portion of such air in proximity to but out of contact with the saws to remove the trash thrown off from the saw teeth, and other means to 105 direct a portion of the first mentioned air against the saw teeth to remove the cleaned lint therefrom.

3. In a saw gin, the combination with the 110 saws, of an air flue having a duct leading into proximity to the saws, means to direct a portion of the air in said duct in proximity to but out of contact with the saws in order to carry off the trash thrown off from the saw teeth, and means to direct another 115 portion of the air in said duct directly against the saw teeth, to remove the cleaned lint therefrom.

4. In a saw gin, the combination with the 120 saws, of means to direct a blast of air away from and out of contact with the peripheries of the saws, to remove the trash thrown off from the saws by centrifugal force, and means to direct a blast of air from the same source against the lower portions of 125 the saws beyond the point where the trash is removed from the same.

5. In a saw gin, the combination with the 130 saws, of a trash chamber adjacent the same, and having a discharge aperture or slot at

- its lower portion, an adjustable plate to control said aperture, a trash flue, and a trash duct connecting the aperture of the trash chamber with said trash flue and into which 5 a blast of air is discharged.
6. In a saw gin, the combination with the saws, of a trash duct into which the trash is thrown from said saws, means to direct a blast of air through said duct, a trash flue 10 into which said duct discharges, and having an outlet, and means to admit air to said flue to prevent the accumulation of the trash therein.
7. In a saw gin, the combination with the saws, of an air flue, a duct leading from said flue to discharge against the saws and thereby remove the lint from the same, and a port in connection with said air flue to induce a draft away from the saws, to remove 15 the liberated lint from the machine.
8. In a cotton gin, a gin saw, a dust chute and a condenser chute, each leading from a point adjacent to the saw, and a dividing-block interposed between the two chutes and 20 forming in connection therewith air blast passages respectively leading into the mouths of the chutes, with the air blast passage leading into the dust chute directed to expel the dust, etc., thrown off at the upper 25 portion of the saw without impinging on the latter, and the air passage leading into the condenser chute directed to remove the cotton adhering to the saw teeth.
9. In a cotton gin, a gin saw, a dust chute 30 leading from a point adjacent to the saw, a condenser chute leading from a point adjacent to the saw and below the dust chute, an air supply duct leading into the gin between said chutes, and a dividing-block ar- 35 ranged between the chutes adjacent to the saw and forming in connection with the chutes, air blast passages directed therein, the air blast passage directed into the dust chute arranged out of the path of the saw.
10. In a cotton gin, a gin saw, a dust chamber adjoining the upper portion of the saw, a chute leading from the lower portion of the chamber, a whipping-board cooperative with the saw, and a nozzle to direct a blast of air into the chute, directed 45 thereto between the lower wall thereof and the whipping-board.
11. In a cotton gin, a gin saw, a dust chamber adjoining the upper portion of the saw, a discharge chute inclining upwardly 50 and outwardly from the bottom of the chamber, a condenser chute leading from a point adjacent to the lower portion of the saw, an air inlet chamber arranged intermediate 55 the two chutes, and a dividing block interposed between the two chutes and forming in connection therewith air-blast passages, with one of said passages directed into the mouth of the discharge chute at the bottom of the dust chamber, and the other of 60 said passages directed into the mouth of the condenser chute and against the lower portion of the saw.
12. In a cotton gin, a gin saw, a dust chamber adjoining the upper portion of the saw, a discharge chute leading from the lower portion of the chamber, a condenser chute leading from a point adjoining the lower portion of the saw below the dust chamber, and air-blast passages, one of 65 which is separated from the saw and directed into the mouth of the discharge chute at the bottom of the dust chamber, and the other into the mouth of the condenser chute and against the adjoining portion of the 70 saw.
- In testimony whereof I affix my signature, in presence of two witnesses.
